UNITED STATES PATENT OFFICE

172,909

LETTER SCALE OR THE LIKE

William Stelzer, Summit, N. J.

Application October 20, 1953, Serial No. 27,249

Term of patent 3½ years

(Cl. D52—10)

To all whom it may concern:

Be it known that I, William Stelzer, a citizen of the United States, residing at Summit, in the county of Union and State of New Jersey, have invented a new, original, and ornamental Design for a Letter Scale or the like, of which the following is a specification, reference being had to the accompanying drawing, forming part thereof.

Fig. 1 is a plan view of a letter scale showing my new design;

Fig. 2 is a front elevation thereof; and
Fig. 3 is a side elevation.

I claim:

The ornamental design for a letter scale or the like, as shown.
